1,972,771

APPARATUS FOR LIQUEFYING SOLID CARBON DIOXIDE

Walter S. Haid, Tulsa, Okla., and Philip A. H. Terrell, Washington, D. C.

Application December 15, 1932, Serial No. 648,088

15 Claims. (Cl. 62—91.5)

The invention relates to liquid gas generators, for instance of the type wherein solidified carbon dioxide is placed in a covered chamber of a single container sublimed and transferred 5 through valve means to a second container chamber in the same container and prevented from retracing its course to the first chamber thereby allowing the cover of the first chamber to be opened for refilling purposes; the valve means 10 being disposed entirely within the container and automatically operated by pressure within the chambers.

A further object is to provide a carbon dioxide liquefier in the form of a single container having a covered chamber for the reception of solidified gas, a second chamber, valve means between said chambers entirely within the container and controlled by pressure of gas generated in a manner whereby upon opening of the cover to the 20 generating chamber escape of gas from the second chamber will be prevented, thereby allowing easy manipulation of the cover and preventing loss of gas while refilling.

A further object is to build up the single container from tubular members having closed ends telescopically disposed in open ends, to which the closed ends are welded, thereby obviating the necessity of welding partitions between the sections which are hard to make water and gas 30 proof against leakage, especially of gas, under high pressure.

A further object is to form the closed ends of the casing sections by a drawing operation, thereby forming an absolutely leakproof partition between the various chambers, and the atmosphere, after the welding operation.

A further object is to shoulder the closed drawn ends of the casing sections, thereby allowing a relatively long telescopic engagement and welding surface if so desired.

A further object is to provide discharge pipe means whereby gas generated in the various chambers may be by-passed from chamber to chamber as desired, or removed therefrom for 45 discharge to apparatus, for instance a soda water fountain or bottling machine as desired.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

55 In the drawings:

Figure 1 is a view in elevation of the gas generator.

Figure 2 is a vertical longitudinal sectional view through the generator shown in Figure 1.

Figure 3 is a view in elevation of another form 60 of generator formed from a number of sections and having a check valve therein.

Figure 4 is a vertical longitudinal sectional view through the generator shown in Figure 3.

Figure 5 is a view in elevation of a further form 65 of the invention showing a plurality of chambers in a single tank, and discharge means therefrom.

Figure 6 is a horizontal sectional view taken on line 6—6 of Figure 5.

Figure 7 is a vertical transverse sectional view 70 through one end of the device shown in Figure 5.

Figure 8 is a view in elevation and partly in section of a two compartment type of machine.

Figure 9 is a further modification of the two cylinder type machine with valve connection 75 between the same.

Referring to the drawings, and particularly to Figures 1 and 2, the numeral 1 designates the upper section of the casing, the lower end of which is bulged as shown at 2, and is disposed in the upper open end 3 of the lower section 4, as clearly shown in Figure 2. The lower section 4 has its lower end closed as shown at 5, and formed integral therewith as the bulged end 2 of the upper section 1, preferably by a drawing operation. After the lower end of the section 1 is disposed in the upper open end 2 of the section 4, the adjacent section ends are welded together as shown at 6, thereby forming a leak-proof connection. Heretofore it has been the practice to form the casing 90 from tubular sections open at their ends and to weld a bottom on the lower end of the lower section and a partition between the sections so as to form upper and lower chambers 7 and 8.

Where a partition is welded to form the chambers and also a bottom on the lower section, it is extremely difficult to get leak-proof connections in a container adapted to hold a gas under high pressure, for instance carbon dioxide gas under a pressure from twelve hundred to three thousand pounds, and by drawing the ends 2 and 5 and forming the same integral with the casing section, it is obvious it will only be necessary to make the single weld as shown at 6, thereby reducing the amount of welding to a minimum, consequently 95 the possibility of leakage.

Chambers 7 and 8 are provided with a by-pass pipe 9, so that gas generated from solid carbon dioxide in the upper chamber 7 may be stored in the lower chamber 8 by manipulating the valves 100 105 110

10 carried by pipe 9, gas may be discharged from either chamber through a common discharge pipe 11 when the valve 12 is open. Pipe 11 may lead to any suitable source of discharge, for instance a 5 soda fountain or a bottling apparatus. By providing the two chambers, the lower chamber 8 may be cut off from the upper chamber when the cover 13 is opened for replenishing the chamber 7 with solid carbon dioxide from time to time and 10 without interfering with the operation of apparatus to which gas is being delivered. By-pass pipe 9 is provided with fracture valves 14 for relieving excessive pressure within the chambers 7 and 8. It will be noted that a single cylinder with 15 two compartments is formed with the minimum amount of welding and that the device may be supported in a stand 15 if desired.

Referring to Figures 3 and 4, in this form, three chambers 15, 16 and 17 are provided in a single 20 cylinder and the chamber 15 in which the solid carbon dioxide is received is carried by an upper section 18, the lower drawn end 19 of which is telescopically received within the upper open end 20 of the intermediate casing section 21. The 25 drawn end 19 is of smaller diameter than the casing section 18, thereby forming a shoulder 22 annularly around the device and resting on the upper end 20 of the intermediate section 21 and is welded thereto at 23. Intermediate section at 30 its lower end is provided with a drawn portion 24, similar to the drawn portion 19 of the upper section 18 and telescopically engages in the upper end of the lower section 25 and is welded thereto at 26, therefore it will be seen that the three sections 18, 20 and 25 form three chambers 15, 16 35 and 17 with only two welds at 23 and 26, consequently the amount of welding is reduced to a minimum.

The bottom 19 of the upper casing section 18 is 40 provided with a check valve 27, whereby as solid carbon dioxide sublimes on the perforated bottom 28 in the casing chamber 15 and expands, it will pass into the chamber 16, and when the cover 29 is open for replenishing the solid carbon dioxide 45 in the chamber 15 valve 17 will close under pressure from chamber 16, thereby preventing loss of gas. In this form, all of the chambers 15, 16 and 17 may have a by-pass connection 30 controlled by valves 31, 32 and 33 whereby gas from either 50 or all of the chambers may be discharged through a common discharge pipe 34, or entirely cut off therefrom if desired. Applicant does not limit himself to the particular by-pass arrangement, as it is obvious this can be eliminated, particularly 55 in by-passing from chambers 15 to 16, as this is taken care of in one way by expansion through check valve 27.

Referring to Figures 5 to 7 inclusive wherein a further modification is shown, in this form the 60 device is in the form of a tank having a plurality of chambers 35, 36 and 37 connected by a by-pass pipe 38 as clearly shown in Figure 6. By-pass pipe 38 is provided with a plurality of valves 39 by the manipulation of which the generated gas is distributed to the various chambers or to the common discharge pipe 40 having a valve 41. In this form the solid carbon dioxide is first placed 65 in the chamber 35 by removal of the cover 42 and is replenished from time to time in the usual manner, but after the manipulation of the valves 70 39 to cut off back flow of gas to the chamber 35 during the refilling operation. Although the various chambers in the devices shown are shown in vertical positions, it is to be understood that 75 applicant may construct the machine so that it

can be used in a horizontal position, particularly the form shown in Figures 5 to 7 inclusive.

From the above it will be seen that a liquefier is provided, particularly adapted for the sublimation of solid chemicals, particularly carbon dioxide, that the amount of welding is reduced to a minimum by the particular construction of drawn ends as clearly shown in Figures 1 to 4 inclusive, and that transfer means is disposed entirely within the cylinders for cutting off the back flow of previously sublimed gas from one compartment to the original generating compartment. Applicant is well aware of the present use of machines whereby the transfer of gas is controlled from the outside of the cylinder.

Referring to Figure 8, in this form of the invention, which is of the vertical or soda water type, the numeral 45 designates an upper compartment and 46 a lower compartment, however these compartments are in separate containers 47 and 48 supported on a base 49. Connecting the upper container 47 into which the solid carbon dioxide is placed in a discharge pipe 50 having a check valve 51 therein, which opens as the solid carbon dioxide sublimes in the compartment 100 45 and enters the compartment 46. In this form the containers 47 and 48 are provided with valve control discharge pipes 52 and 53, through which the gas may be piped to any suitable source of discharge, for instance carbonating apparatus 105 of the soda fountain.

Referring to Figure 9 the construction and operation of the device is substantially the same as shown in Figure 8, with the exception in Figure 8 the check valve 51 is entirely within the device, while in Figure 9 the connecting pipe 50a is provided with a valve 54, whereby the operator may cut off the upper compartment 45 when the cover 56 is opened for refilling purposes. The discharge pipes 57 and 58 from the containers 115 47 and 48 are connected together by a by-pass pipe 59 having a common discharge pipe 60, which may lead to any suitable source of discharge. Pipes 57, 28 and 60 are provided with control valves 61 by means of which the flow of gas may 120 be controlled between the compartments or from the device. Conventional fracture valves 62 are provided for relieving excess pressure.

The invention having been set forth what is claimed as new and useful is:

1. A gas liquefier comprising a single cylinder formed from a plurality of sections having open and closed ends telescopically engaged, said open and closed ends being welded together.

2. A gas liquefier comprising a single cylinder 130 formed from a plurality of sections, said sections having integrally formed closed ends and open ends, said closed ends being disposed within the opened ends and welded thereto.

3. A gas liquefier comprising a single cylinder 135 formed from a plurality of sections having open and closed ends, the closed ends being formed integral with the sections and disposed within the open ends of the sections and leak-proof connections between said sections where they engage. 140

4. A gas liquefier comprising a single container formed from a plurality of chambered sections, said sections having integrally formed closed ends, said closed ends engaging the open ends of adjacent sections and a leak-proof connection between said sections where they engage. 145

5. A single casing gas liquefier formed from a plurality of sections, said sections having closed integral ends, open ends carried by said sections and in which the closed ends of adjacent 150

- sections are disposed and leak-proof connections between said sections where they engage. 80
6. A single casing gas liquefier formed from a plurality of sections, said sections having integrally closed drawn ends disposed within adjacent open ends of adjacent sections and leak-proof connections between said sections where they interengage. 85
7. The combination with a single casing gas liquefier having a plurality of chambers therein, means whereby a gas to be sublimed may be placed in one of said chambers and transferred by expansion into the other chamber and held against retrograde movement entirely by means 90
- 15 located within the single casing.
8. The combination with a gas liquefier casing having a chamber for the reception of a solid chemical to be sublimed and a chamber into which the gas is transferred from the first mentioned chamber, of means located entirely within the casing and pressure controlled whereby gas generated in the first mentioned chamber is transferred by expansive pressure into the second chamber and held against retrograde movement into the first chamber upon release of pressure in the first chamber. 95
9. The combination with a gas liquefier comprising a single casing having a chemical receiving chamber and a transfer chamber, a partition between said chambers within the casing, of a check valve in said partition and forming means located entirely within the casing and pressure controlled, whereby gas generated in the chemical receiving chamber will be transferred to the transfer chamber and held against retrograde movement upon release of pressure in the chemical receiving chamber. 100
- 30 10. A gas liquefier comprising upper and lower casings each forming a chamber, said casings being in spaced relation and connected together by a relatively short rigid conduit through which gas from the upper chamber can pass to the lower chamber and valve means in said conduit and forming means whereby the upper casing chamber may be shut off from the lower casing chamber for refilling purposes and a discharge means for the lower casing. 105
11. A gas liquefier comprising spaced upper and lower casings each forming a chamber, a cover carried by the upper casing and adapted to be opened for placing material in the upper casing to be liquefied, a relatively short rigid conduit connecting said casings and having means located entirely within the conduit whereby expanding gas in the upper chamber will pass through said means to the lower chamber and be cut off from retrograde movement by said means upon opening of the cover of the upper casing. 110
12. A device as set forth in claim 8 including a manifold connection between the chambers, a discharge means in connection with the manifold means and means whereby gas from any of the chambers may be discharged through the manifold. 115
13. A device as set forth in claim 8 including means for discharging gas from the chambers other than through the chambers. 120
14. A device as set forth in claim 10 including a discharge means for the upper chamber. 125
15. A device as set forth in claim 10 including a manifold connection between the casing chambers and forming a discharge means for any or all of the chambers. 130
